CLAIM

I claim the ornamental design for a vest for use with a video game system, as shown and described.

DESCRIPTION

FIG. 1 is a front elevational view of a vest for use with a video game system showing my new design the transmitter cable being shown throughout the views being of undetermined length; and the broken lines shown throughout the views being understood to represent conventional stitching. FIG. 2 is a rear elevational view thereof; FIG. 3 is a right side elevational view thereof; FIG. 4 is a left side elevational view thereof; FIG. 5 is a top plan view thereof; and, FIG. 6 is a bottom plan view thereof.
